UNITED STATES PATENT OFFICE.

JAMES FRANCIS WOOD, OF PHILADELPHIA, PENNSYLVANIA.

HOLDER FOR BLACKING.

SPECIFICATION forming part of Letters Patent No. 360,335, dated March 29, 1887.

Application filed January 10, 1887. Serial No. 223,841. (No model.)

To all whom it may concern:

Be it known that I, JAMES FRANCIS WOOD, a citizen of the United States, residing at the city and county of Philadelphia, and State of Pennsylvania, have invented certain new and useful Improvements in Holders for Blacking, &c., of which the following is a full, clear, and exact description, reference being had to the accompanying drawings, of which—

10 Figure 1 is a side elevation in the closed position. Fig. 2 is a longitudinal vertical section, the lid of the box or holder being thrown back. Fig. 3 is a plan of Fig. 1.

The object of this invention is to provide a 15 holder for blacking or other material, or for holding boxes containing the blacking, &c., which may be readily opened and closed and retained in the respective positions; and it consists in the combination, with a box of suitable shape, with a lid fitting thereon, of a handle attached to said box, a thumb-lever attached to the lid of the box and pivoted to the said handle, together with a spring arranged to bear against the cam-lever, whereby 25 the lid is retained in the closed and open positions, respectively.

The improvement is clearly shown in the annexed drawings, in which A marks the box, and B its lid. To the box is secured, by soldering or otherwise, the forward extension, c', of a handle, C, which latter is provided with lugs D, adjacent to the side of the box A. To said lugs is pivoted, at x, a cam-lever, E, to the forward arm, e', of which is secured the 35 lid B, whilst its bent rear or short arm has an upward projection, e'', that constitutes a thumb-piece for operating the lever. The upper portion of the box is beveled inwardly and the rim of the lid is correspondingly beveled outwardly, as shown; so as to insure a close and easy fit of the one with the other, the lever to which the lid is secured being, of course, so pivoted to the handle that the lid will close properly upon the box.

40 It will be seen that when the handle is grasped and the thumb pressed down upon the projection e'' of the lever the lid will be raised—that is, brought from the position seen in Fig. 1 to that of Fig. 2. In order, however, 45 to retain the lid in these respective positions,

I provide a spring, F, one end of which is secured to a cross-bar, g, in the handle and bears upon another cross-bar, g', while its free end bears against the lower side of the short arm of the thumb-lever. Obviously, when the 55 lid is shut down upon the box, the force of the spring tends to retain it in place, and it is also obvious that it (the lid) will be held in the open position, it being understood that the construction is such as shown, whereby the 60 cam portion of the short arm of the lever is permitted to be brought past the pivotal center, although I may remark that it is not necessary that it should pass the center, as the friction will usually be sufficient to prevent the lid from being forced down by the 65 spring, although the center has not been passed.

I do not limit myself to the precise form or construction shown either of the box or lever and spring devices; but

What I claim as new, and wish to secure by Letters Patent, is—

1. In a holder for blacking, &c., the combination of the handle secured to the bottom of 75 the box and provided with the vertical lugs D adjacent to said box, the cam-lever secured to the lid and pivoted to said lugs, together with the flat spring secured to said handle and adapted to bear against the under side of 80 said cam-lever, so as to retain the attached lid in the closed and open positions, respectively, substantially as and for the purpose set forth.

2. In a holder for blacking, &c., the combination of the box, the handle secured to the 85 bottom thereof and provided with the lugs D, the lid, the cam-lever pivoted to said lugs and having its forward arm secured to said lid and its rear arm bent upward to form a thumb-piece, and the flat spring attached to said handle 90 and adapted to bear against the under side of said cam-lever, substantially as and for the purpose specified.

In testimony whereof I have hereunto affixed my signature this 9th day of December, A. D. 95 1886.

JAMES FRANCIS WOOD.
